[57] CLAIM

The ornamental design for an insulated jug or the like, as shown and described.

DESCRIPTION

FIG. 1 is a top, front, and right side perspective view of an insulated jug or the like, showing my new design; FIG. 2 is a rear elevational view thereof; FIG. 3 is a front elevational view thereof; FIG. 4 is a right-side elevational view thereof, the left side being a mirror image thereof; and FIG. 5 is a top plan view thereof.
The bottom of the insulated jug, or the like is plane and unornamented.
